(57) **CLAIM**

The ornamental design for a toaster tray, as shown and described.

DESCRIPTION

FIG. 1 is a top side perspective view of a toaster tray; FIG. 2 is a bottom side perspective view of the toaster tray; FIG. 3 is a top plan view of the toaster tray; FIG. 4 is a front side elevational view of the toaster tray; FIG. 5 is a left side elevational view of the toaster tray; FIG. 6 is a bottom plan view of the toaster tray; and, FIG. 7 is a cross-sectional view taken through line 7-7 of the toaster tray of FIG. 6.

The rear side elevational view of the toaster tray is a mirror image of the front side elevational view of FIG. 4. The right side elevational view of the toaster tray is a mirror image of the left side elevational view of FIG. 5.
